(57) **CLAIM**

The ornamental design for a headband with integral hairnet, as shown and described.

DESCRIPTION

FIG. 1 is a top plan view of a headband with integral hairnet showing my new design;

FIG. 2 is a top isometric view thereof with back portions visible through the netting;

FIG. 3 is a left side elevation view thereof;

FIG. 4 is a front elevation view thereof;

FIG. 5 is a right side elevation view thereof;

FIG. 6 is a back elevation view thereof;

FIG. 7 is a bottom plan view thereof; and,

FIG. 8 is a bottom perspective view thereof.

The broken lines represent environmental structure that forms no part of the claimed design.
